UNITED STATES PATENT OFFICE.

RUFUS W. SCOTT, OF NEW YORK, N. Y., ASSIGNOR TO HEMPHILL COMPANY, OF CENTRAL FALLS, RHODE ISLAND, A CORPORATION OF MASSACHUSETTS.

SEAMLESS HIGH-SPICE STOCKING.

Application filed October 14, 1922. Serial No. 594,524.

To all whom it may concern:

Be it known that I, RUFUS W. SCOTT, a citizen of the United States, and a resident of the city of New York, in the county of New York and State of New York, have invented an Improvement in Seamless High-Splice Stockings, of which the following description, in connection with the accompanying drawings, is a specification, like characters on the drawings representing like parts.

This invention relates to seamless stockings. In order that the principle of the invention may be readily understood, I have disclosed certain embodiments of the stocking of my invention in the accompanying drawings, wherein—

Fig. 1 is a side elevation of a seamless stocking embodying my invention;

Fig. 1^a is a side elevation of a stocking partly broken away showing a modified form of my invention; Fig. 1^b is a side elevation of the lower part of the stocking and illustrating another modified form of my invention.

Fig. 2 is an enlarged detail of a portion of the stocking at the high splice and representing the stitch formation;

Fig. 3 is a view similar to Fig. 1 of a somewhat modified form of my invention; and

Fig. 4 is a view similar to Fig. 2, but illustrating that form of my invention shown in Fig. 3.

The stocking of my invention is a so-called circular or seamless stocking knitted upon a circular machine having means for forming the heel and toe pockets, such as narrowing and widening pickers. While any suitable mechanism may be employed in the production of the stocking, the machine should be equipped with means for introducing the main knitting yarn, and for introducing a reinforcing yarn or yarns at the desired point or points, and desirably with means for changing the stitch length in the leg as the knitting progresses.

My invention pertains more particularly to the so-called high splice of the stocking which is combined with a mock seam which may be a structural variation of the stitches, such, for example, as a line of tuck stitches of the length of the high splice or other suitable length, or may be a sewed line of

stitches desirably of the length of the stocking to the heel.

Desirably the high splice is of very narrow width and is itself desirably made of two very narrow longitudinal stripes at either side of and close to the back median line of the stocking, the mock seam being located in the narrow space between said two stripes and being of any suitable character, but desirably either of tuck stitches or formed as a line of sewing machine stitches.

Referring more particularly to the drawings, and first to that form of my invention shown in Figs. 1 and 2, the stocking is indicated generally at 1, it having desirably a seamless heel 2 and toe 3. One of the said very narrow stripes of the narrow high splice is indicated at 4 in Fig. 1, and the two very narrow stripes are indicated at 4, 5 in Fig. 2.

The stocking may be knitted from any suitable material, as, for example, silk. The stocking may be knitted in any usual or approved manner until the top of the high splice 4, 5 is reached, though, if desired, the line of tuck stitches may commence at or near the top of the stocking instead of at the top of the high splice, as indicated in Fig. 1^a, where such line of tuck stitches is indicated at 5'. For convenience of description, it will be assumed that the line of tuck stitches begins at the top of the high splice. In such case, and in any suitable manner, I introduce one or more lines of tuck stitches, and herein I have represented two such lines at 6, 7 in Fig. 2 between which may be a line or wale of plain stitches 8. The said line or lines of tuck stitches may be introduced in any suitable manner, as by the employment of a tucking cam which co-acts with one or more needles having special length butts.

The narrow stripes 4, 5 are in this form of my invention produced by introducing a reinforcing yarn 9 from a suitable yarn guide or finger, and to sufficient needles to form a stripe 4 of the desired width, which may be greater than the width actually shown in Fig. 2, said figure being diagrammatic merely. When the reinforcing yarn has reached a wale adjacent to or, it may be actually adjoining the nearest line of tuck stitches, said thread is floated across or past the line or lines of tuck stitches, and is reintroduced to the needles at the opposite side

of said line or lines of tuck stitches, and is interknitted with the regular thread to form the narrow stripe 5 of the width of the stripe 4, after which the said reinforcing thread is floated from the outer edge of the stripe 5 back to the outer edge of the stripe 4, whereupon the described procedure is repeated until the entire high splice composed of the stripes 4 and 5 is completed, and the 10 entire line of tuck stitches is also completed.

It will be observed that in this form of my invention I have provided a very narrow high splice itself composed of two still narrower longitudinal stripes between which 15 is a mock seam that does not enter into or bind down the floating threads and does not penetrate the high splice itself.

In that form of my invention shown in Figs. 3 and 4, the stocking, which otherwise 20 may be the same as that shown in Fig. 1, is provided with a very narrow high splice composed of two very narrow longitudinal stripes, one of which is indicated at 10 in Fig. 3 and which are both shown at 10, 11 in 25 Fig. 4. The composite high splice is desirably of substantially the width indicated in Fig. 1, but the reinforcing thread 12, which is introduced to the needles for the stripe 10, is merely interknitted with the needles at 30 that side of the stocking where the stripe 10 is formed, and at the inner edge of said stripe the thread is floated back to the outer edge of the same stripe, and this process is continued until the entire stripe 10 is completed. 35 Simultaneously with the formation of the stripe 10, the stripe 11 is formed and in the same way, and either from an entirely distinct thread or in any other suitable manner.

Thus I form a narrow high splice composed 40 of two very narrow longitudinal stripes, each of which has incorporated therewith a reinforcing thread, and between said stripes 10 and 11 there exists several rows or wales of non-reinforced stitches. After the stocking 45 is completed, I run a line of sewing machine stitches 13 between the stripes 10 and 11, and at least to the upper edge of said stripes, but desirably to the upper end of the stocking, or at least to the welt portion 50 thereof.

It will be seen that in this form of my invention the mock seam does not engage the floating threads, and that therefore both forms of my invention have this common 55 characteristic of non-engagement of floating threads by the mock seam.

While I have specifically shown and described mock seams composed of tuck stitches and sewing machine stitches, it is to 60 be understood that any suitable types of mock seam may be employed provided they do not enter the substance of the high splice or bind down floating threads thereof.

The single reinforcing yarn 9 of that form 65 of my invention shown in Figs. 1 and 2 and

the two reinforcing yarns 12, 14 of that form of my invention shown in Figs. 3 and 4 may be introduced in any well known manner, as, for example, by one or two special yarn fingers at a point or points where the needles 70 are divided by a special cam or cams, so that the needles which are not to take the auxiliary yarn or yarns are either elevated or depressed, and the auxiliary yarn is delivered or the auxiliary yarns are delivered 75 to the other needles, which, of course, may be of any suitable number, at each side of the back median line of the stocking.

I have stated that the mock seam may be of any suitable character. If it be a structural variation of the knitted fabric it may be composed of tuck stitches or draw stitches and any suitable number of wales or lines of such stitches may be employed. For example, instead of employing two wales of 80 tuck stitches separated by a wale of plain stitches, I may employ two adjoining wales of tuck stitches, or a single wale of tuck 85 stitches. I have found that two adjoining wales of tuck stitches produce mock seams of 90 proper proportions.

The thread of which the main portion of the stocking is composed is preferably silk, and the reinforcing thread or threads may be of some contrasting material, such, for 95 example, as cotton. In such case, and referring to that form of my invention shown in Fig. 2, the mock seam is composed wholly of the silk throughout, and therefore contrasts markedly with the adjacent reinforcement areas, which are themselves both composed of silk, and cotton or other non-silk threads.

While I have shown my invention as embodied in a narrow high-splice, it is evident 100 that within the scope of my invention the high-splice may be of any suitable width and may be even of the full width of the heel. While I have shown the high-splice as having parallel sides, it is evident that 110 the high-splice may be otherwise shaped. For example, it may be of a tapering or substantially triangular shape, the apex of the triangle being uppermost, as shown in Fig. 1^b at 4'.

I do not herein claim the subject matter disclosed and claimed in my co-pending application Serial Number 592,676, filed October 6, 1922, for seamless stocking and method of making the same—said application disclosing a mock seam of tuck stitches and a stripe paralleling said line of tuck stitches at each side thereof with float yarn connections between the auxiliary yarn of 120 said stripes.

Having thus described two illustrative embodiments of my invention and the best modes known to me for producing the same, I desire it to be understood that although specific terms are employed, they are used 125

in a generic and descriptive sense and not for purposes of limitation, the scope of the invention being set forth in the following claims.

5 Claims:

1. A so-called seamless stocking having a high splice of substantially less width than the heel and itself composed of two very narrow stripes wherein reinforcing yarn is

10 interknitted with the regular yarn, said stripes being spaced apart, and a mock seam between the said stripes of said high splice and extending longitudinally thereof.

2. A so-called seamless stocking having a 15 high splice of substantially less width than the heel and itself composed of two very narrow stripes wherein reinforcing yarn is interknitted with the regular yarn, the reinforcing yarn being floated at the back of the said two stripes, said stripes being spaced apart and extending longitudinally thereof.

3. A so-called seamless stocking having a 20 high splice of substantially less width than the heel and itself composed of two very narrow stripes wherein reinforcing yarn is interknitted with the regular yarn, the reinforcing yarn being floated at the back of the said two stripes, said stripes being spaced apart and across which space the yarn is floated, and a mock seam constituting a structural variation between said stripes and extending longitudinally thereof.

4. A so-called seamless stocking having a 25 high splice of substantially less width than the heel and itself composed of two very narrow stripes wherein reinforcing yarn is interknitted with the regular yarn, the reinforcing yarn being floated at the back of the said two stripes, said stripes being spaced apart and across which space the yarn is floated, and a mock seam of tuck stitches between said stripes and extending longitudinally thereof.

45 5. A so-called seamless stocking knitted from a main yarn and having a high splice composed of two narrow lengthwise extending, adjacent stripes wherein a reinforcing yarn is interknitted with the main yarn, said reinforcing yarn being of a character contrasting with the main yarn, said stripes

50 contrasting with the main yarn, said stripes

being spaced slightly apart, and a mock seam between said stripes of the high splice, said mock seam being composed of a line of tuck stitches formed only of the material of the main yarn, whereby said mock seam contrasts with the reinforcing yarns of the said stripes.

6. A so-called seamless stocking knitted from a main yarn and having a high splice 60 composed of two narrow lengthwise extending, adjacent stripes wherein a reinforcing yarn is interknitted with the main yarn, said reinforcing yarn being of a character contrasting with the main yarn, said stripes 65 being spaced slightly apart, and a mock seam between said stripes of the high splice, said mock seam being composed of a double line of tuck stitches, there being a line of regular stitches therebetween.

7. A so-called seamless stocking having a 70 high splice which is composed of two stripes wherein reinforcing yarn is interknitted with the regular yarn, said stripes being placed slightly apart and a mock seam between the stripes of said high splice and extending longitudinally thereof.

8. A so-called seamless stocking knitted from a main yarn and having a high splice 80 composed of two narrow lengthwise extending, adjacent stripes wherein a reinforcing yarn is interknitted with the main yarn, said reinforcing yarn being of a character contrasting with the main yarn, said stripes being spaced slightly apart, and a mock seam 85 between said stripes of the high splice.

9. A so-called seamless stocking knitted from a main yarn and having a high splice 90 composed of two narrow lengthwise extending, adjacent stripes wherein a reinforcing yarn is interknitted with the main yarn, said reinforcing yarn being of a character contrasting with the main yarn, said stripes being spaced slightly apart, and a mock seam between said stripes of the high splice, said 95 mock seam being composed only of the material of the main yarn, whereby said mock seam contrasts with the main and reinforcing yarns of the said stripes.

In testimony whereof I have signed my 100 name to this specification.

RUFUS W. SCOTT.
